UNITED STATES PATENT OFFICE

2,139,156

DETACHABLE SCREEN FOR AUTOMOBILES

Leroy G. Gill, Detroit, Mich.

Application October 2, 1936, Serial No. 103,680

2 Claims. (Cl. 156—14)

My invention relates to screens for automobiles, and its principal object is to provide a screen which can be easily and quickly attached to and removed from the windows of the vehicle.

5 It is apparent that, notwithstanding the increasing number of accidents which are caused during summer driving by the entrance of insects, birds, and so forth through the open windows of vehicles, the trouble and expense of putting in and taking out screens has prevented their general use.

Another object of my invention is to provide means whereby the driver of a vehicle may extend his hand through a window to which my 15 screen is applied in order to signal other drivers.

Another object of my invention is to provide a screen for the purpose set forth which is economical to manufacture, neat in appearance, and reliable in operation.

20 A further object of my said invention is to provide means interchangeable with the screen which may be employed during the winter season for preventing the condensation of moisture upon the window and thus obstructing the vision of 25 the operator.

With these and other objects in view the invention consists in the improved construction, arrangement, and combination of parts which will be hereinafter fully described, reference being 30 had to the accompanying drawing, which illustrates a preferred embodiment thereof, in which drawing—

Figure 1 is an elevation looking from the interior of the vehicle showing one method of applying my device to the front window on the driver's side.

Figure 2 is a section on line 2—2 of Figure 1.

Figure 3 is a fragmentary section similar to Figure 2 but drawn to an enlarged scale in order 40 to show certain details more clearly.

Figure 4 is a fragmentary elevation drawn to enlarged scale showing one method of locking the screen in place.

Figure 5 is an elevation showing a hinge for 45 carrying a swingable portion of the screen.

Figure 6 is an elevation showing a retainer for the screen frame, and

Figure 7 is a horizontal section taken on line 2—2 of Figure 1 illustrating the application of my 50 invention to a one-piece screen.

Like characters designate corresponding parts throughout the several views.

1 is the door of the vehicle and 2 designates the molding which defines the window opening there- 55 in, the said molding being usually of sheet metal

as shown. 3 is the window sash slidable up and down within the openings 4 in the molding, the said sash being of course lowered within the body of the door when the screen is in use. The openings 4 are lined with the usual strips 41 of 5 felt or other soft material which surround the edges of the sash.

Around the inner face 21 of the molding is a metal frame 5 provided with a flange portion 51 which extends inwards to the back surface of 10 the molding and engages therewith, as shown more clearly in Figure 3. Within the frame 5 is also a channel 51' which extends therearound and is adapted to receive the edge 61 of the wire screen 6, the said edge consisting of a U-shaped 15 piece of metal extending around the periphery of the screen and permanently secured thereto. In order to secure the screen in place, the frame 5 is provided with a second member 52, the inner edge of which is provided with a flange 53 which 20 engages a flange 54 on the main portion of the frame and is provided with an inturned edge 55 which engages the stiffened edge 61 of the screen and retains it in place. The member 52 as a 25 whole is secured in place at one end by an arcuate projection 22 upon the molding and at the other end by a lock 7 of the tumbler type having a bolt 71 adapted to engage a slot in the molding and provided with a key 72.

In all of the windows of the vehicle which are 30 provided with sliding sashes, with the exception of the driver's window, the frame as above described will extend entirely around the window opening and the screen will be in one piece. In the window near the driver however, in order to 35 enable him to extend his hand therethrough, I provide a separate screen 6A which is connected by hinges 8 to a vertical cross member 56 upon the main frame, and the screen portion 6A is provided with a sub-frame 9 and with pivoted 40 catches 91 adapted to engage the main frame 5 and to prevent the screen 6A from being pushed outwards when the car is parked with the doors locked. A coil spring 92 upon the hinge tends 45 to keep the portion 6A of the screen in a closed position, the said spring being strong enough to prevent vibration of the parts and at the same time allow it to be manually operated. When the hinged screen 6A is used, the flange 55 is omitted in the opening which receives it. The 50 flange, however, is provided upon the vertical portion 52' of the frame 52. The portion 52' may in this case be secured in the position by other means than the lock 7, such as, for example, the screw 522 which threadedly engages the 55

member 56. In this modification, the fixed portion 6 of the screen is removed by taking off the frame 52, while the hinged portion 6A is removed by taking out the pins of the hinges 8, the frame 5 being left permanently within the window opening.

During the winter season when the screens are not required, I provide in their place sheets of Celluloid or other transparent material having reinforced edges similar to those upon the wire screens and held in position within the frame in the same manner. These transparent sheets, being spaced to some extent apart from the window glass 3, as will be observed from the sectional 15 plan view Figure 3, cause currents of air to pass up close to the inner surface of the glass and so carry away moisture which would otherwise collect upon the surface and obscure the vision of the operator.

20 It will be observed from the foregoing description and by reference to the drawing that I have provided a screen which is simple in construction and convenient to operate, and while I have herein described and shown a preferred embodiment 25 of my invention, it will be understood by those skilled in the art to which the same relates that various modifications in detail may be made without departing from the spirit of the invention as defined in the appended claims.

30 Having thus described my said invention, what

I claim and desire to secure by Letters Patent of the United States is:

1. In a device of the character described, the combination, with an automobile having a window opening therein, of a hollow moulding defining said opening and having a slot extending around the inner face thereof, a frame of channel-like section extending therearound and having its base passing through said slot with one leg of the channel overlying the rear surface of the moulding, a screen having a stiffening member upon its periphery and fitting within said frame, and a cover detachably secured to said frame and adapted to retain said screen therewithin. 15

2. In a device of the character described, the combination, with an automobile having a window opening therein, of a hollow moulding defining said opening and having a slot extending around the inner face thereof, a frame of channel-like section extending therearound and having its base passing through said slot with one leg of the channel overlying the rear surface of the moulding, a screen having a stiffening member upon its periphery and fitting within said frame, a cover detachably secured to said frame and adapted to retain said screen therewithin, and means for securing said cover in place. 20 25
